UNITED STATES PATENT OFFICE.

MANIOUS GARL, OF AKRON, OHIO.

WIND MUSICAL INSTRUMENT.

1,170,627.

Specification of Letters Patent.

Patented Feb. 8, 1916.

Application filed April 3, 1912. Serial No. 688,250.

To all whom it may concern:

Be it known that I, MANIOUS GARL, a citizen of the United States, residing at Akron, in the county of Summit and State of Ohio have invented certain new and useful Improvements in Wind Musical Instruments, of which the following is a specification, reference being had therein to the accompanying drawing.

10 This invention relates to automobile horns and has special reference to an automobile horn which is capable of producing a variety of notes so that tunes may be played thereon.

15 The principal object of the invention is to improve the general construction of devices of this character.

With the above and other objects in view, the invention consists in general of certain 20 novel constructions, and combinations and arrangements of parts, as will be herein-after fully described, illustrated in the drawings, and specifically claimed.

In the accompanying drawings, like 25 characters of reference indicate like parts in the several views, and Figure 1 is a dia-grammatic view of the various parts of the invention assembled. Fig. 2 is a partial de-tail section through the supporting device 30 for the electro-magnets. Fig. 3 is a trans-verse horizontal section through the key-board used in connection with the present invention. Fig. 4 is a similar section with the keys and contact strips removed, the 35 section being arranged to show the support-ing rod for the keys. Fig. 5 is a longitudi-nal section through the key-board. Fig. 6 is a transverse section through the key-board. Fig. 7 is a detail view of the 40 means used for equalizing and maintaining a steady pressure of air to supply the horn or pipes. Fig. 8 is a perspective of the en-tire device assembled, the electrical supply means and air supply means being elimi-nated. Fig. 9 is a horizontal section 45 through the body of the wind chest or means for supporting the whistles or pipes. Fig. 10 is a vertical sectional view through a portion of the wind chest showing the 50 method of mounting the whistles or pipes thereon and also the manner of mounting the solenoids thereon.

This invention consists in general of a 55 key board arranged to close a series of elec-trical circuits indicated at X, a battery Y,

a source of air pressure as the fan Z, and a wind chest supporting a series of horns as indicated at R.

The wind chest as indicated at R is in-tended to seat upon the running board of 60 an automobile or to be placed in any other convenient position, and leading from this windchest to the key board X is a series of wires held in a flexible covering 22 so that the key board may be placed in any 65 convenient position about the automobile. The wind chest consists of a casing having a lower portion or body 23 wherethrough extends a longitudinal channel or passage 24 which is provided with a suitable open-ing which is connected by means of a pipe 26 with a suitable pressure regulator 27 supplied with air from a pipe 28 leading from the fan or blower Z. Extending lat-erally from the portion 23 of the casing 70 are spaced projections 29 each of which contains a pocket 30. Extending down-ward from each of the pockets 30 is a short 75 passage 31 which communicates with a pas-sage 32 bored in from the end of the re-spective projection 29 and adjacent the outer end of the projection is a vertical 80 passage 33. The outer end of each of the passag-es 32 is threaded for the reception of a screw 34 having a head 35. This screw 85 is of such length that by screwing the same in entirely the respective passage 33 may be closed off of the passage 32 while by ad-justing the position of the screw 34 out-wardly the opening between the passag-es 90 32 and 33 may be regulated.

On top of the casing just described is a 95 rectangular plate 36 wherein are threaded openings 37 which correspond with the pas-sages 33 and similar threaded openings 38 alining with the passages 31. Screwed into the several openings 38 are solenoids 39 wherein move cores 40 having enlarged lower ends 41 which normally rest upon the 100 openings 31 and constitute valves which close off these openings from the passage or channel 24. These solenoids are preferably covered with a suitable casing 42. The lower ends 45 of the pipes or whistles 44 are threaded into the apertures 37.

105 It will be plain that if air be supplied to the channel 24 and any one of the solenoids be energized the core of the energized sole-noids will be lifted and air admitted through the passages 31 and 32 and 33 to the respec-110

tive pipe or whistle, thus sounding the note which that pipe or whistle is arranged to produce.

Each of the solenoids has one of its windings connected with the plate 36 as indicated in the diagrammatic view at 46.

Coming now to the circuit closing device. This device consists of a casing 55 of insulating material such as hard wood, ebonite, or the like, although the casing may also be of metal if the proper precautions are taken to insulate the electrical connections therein. The solenoids 39 are electrically connected in a suitable manner to the springs 59 which are actuated by suitable operating keys 61 for closing a circuit with a suitable contact strip 57 whereby the desired solenoid may be energized. As this particular construction is not included in the claims, it is, therefore, not necessary to give a detail description of this structure.

The arrangement of the keys is shown in Fig. 1 and the pipes or whistles and keys are so connected and arranged to produce the following notes from left to right: G, A, B, C, D, E, F, G and A. One of the black keys is adapted to produce F sharp and the remaining keys are adapted to produce a combination of two or more keys, as for instance the black keys from left to right produce G, E, and C; B and D and F and A.

The air pressure for operating the whistles or pipes 44 is obtained from the reservoir 78 of suitable construction.

From the foregoing it will be plain that when the blower is set in operation air will be supplied to the channel 24 and from thence will tend to pass to the several pipes or whistles, the admission of air to any pipe or whistle being controlled by the closing of the electric circuit which permits a current to flow through the proper solenoid. It will also be obvious that the key board may be shifted from place to place in the automobile so that either the driver or those riding with him may use the instrument.

There has thus been provided a simple and efficient device of the kind described and for the purpose specified.

It is obvious that many minor changes may be made in the form and construction

thereof without departing from the material principles thereof, and it is therefore not wished to confine the invention to the exact form herein shown and described but it is wished to include all such as properly come within the scope claimed.

Having thus described the invention, what is claimed as new, is:

1. A base for a wind instrument comprising a body portion provided with a longitudinally extending channel, arms extending from said body portion and provided with pockets leading from said channel and with passages leading from the outer ends of said arms and communicating with said pockets, the outer end portions of said arms being provided with vertical passages leading from the first mentioned passages to the upper faces of said arms, a cover plate covering said channel and provided with openings communicating with said pockets and vertical passages, valves carried by said plate and having their stems passing into said pockets for normally closing the upper ends of said first mentioned passages, and plugs threaded into the outer end portions of said first mentioned passages and extending across the inner ends of said vertical passages when in their innermost position for cutting off the flow of air through said vertical passages.

2. A musical instrument of the class described comprising a body provided with an air channel, a plurality of sound producing elements carried by said body, said body provided with a series of passages communicating with said air channel, said body provided with a second series of passages communicating with said first mentioned passages, said sound producing elements communicating with said second series of passages, means for supplying air to said passages, and means for controlling the flow of air through said first mentioned passages.

In testimony whereof I hereunto affix my signature in presence of two witnesses.

MANIOUS GARL.
